UNITED STATES PATENT OFFICE

2,581,590

SAFETY GAS PILOT WITH DRAFT GUARD

Robert P. Humphrey, Kalamazoo, Mich., assignor
to General Gas Light Company, Kalamazoo,
Mich.

Application April 7, 1950, Serial No. 154,653

7 Claims. (Cl. 158—115)

1

This invention relates to improvements in safety gas pilot with draft guard.

The main objects of this invention are:

First, to provide a safety gas pilot which is highly efficient and is not likely to become clogged or inoperative.

Second, to provide a gas pilot unit which is not likely to be extinguished by drafts.

Third, to provide a gas pilot unit having these advantages which can be installed as a unit in operative relation to a gas burner.

Fourth, to provide a structure having these advantages which is economical in its parts and at the same time strong and durable.

Objects relating to details and economies of the invention will appear from the description to follow. The invention is pointed out in the claims.

A preferred embodiment of the invention is illustrated in the accompanying drawings, in which:

Fig. 1 is a perspective view of a gas burner with my pilot burner unit associated therewith, the valve mechanism being shown conventionally.

Fig. 2 is an enlarged fragmentary view in sections through the main burner.

Fig. 3 is an enlarged fragmentary view partially in vertical section of a commercial embodiment of my pilot burner.

Fig. 4 is a fragmentary plan view of the pilot burner unit of my invention.

In the accompanying drawing, 1 represents the main burner which is provided with a bunsen tube or body member 2 with which the gas nozzle 3 is operatively associated. 4 represents the gas supply valve. The details of this valve form no part of my present invention except that the valve is of a type which is controlled by a thermocouple and which controls the supply conduit 5 of the pilot burner. In the embodiment of my invention illustrated the thermocouple designated generally by the numeral 6 is operatively connected to the valve through the connection conventionally shown at 7.

The pilot burner of my invention as illustrated comprises a burner tube or body member which is mounted on the bracket 9 attached to the lug or stud 10 on the burner. The bracket has vertically spaced support members 11 and 12, the tubular body member or burner tube 13 being fixedly mounted on the top member of the bracket. The supply nozzle 14 is disposed in alignment with the burner tube and is mounted on the bottom bracket member 11. The burner head 15, which in this embodiment illustrated is domed, is sleeved upon the burner tube 13 and

2

is provided with an integral outwardly extending annular flange 16. The burner tube and the burner head have longitudinal registering slots 17 and 18 respectively. The slot 18 in the burner head extends to the top of the head. The burner head is provided with a pilot jet orifice 19 disposed in the side thereof and angularly spaced relative to the slot 18, preferably 90° as illustrated. The burner tube has a thermocouple jet orifice 20 registering with the slot 17 and preferably in spaced relation to the lower end of the slot 17.

The diagonal slot 21 opens to the pilot jet orifice 19 and extends downwardly therefrom and relatively crosswise of the slots 17 and 18, the crossing point being in the plane of the flange 16. The flange has a radial slot 22 extending from its periphery and opening to the longitudinal slots. It will be noted that the flange 16 is spaced above the thermocouple jet orifice 20 and spaced below the pilot jet orifice 19. The thermocouple 6 is disposed in alignment with the jet orifice 20 while the pilot orifice 19 is directed toward the burner, the burner illustrated having a plurality of ignition jet orifices 23 in the side thereof aligned with the pilot orifice 19 and adapted to direct gas toward the pilot orifice or into the path of the pilot flame.

The flame from the thermocouple jet orifice 20 heats the thermocouple which is connected to the control valve so that while heated the control valve for the pilot burner is held in open position; however, in the event of the pilot burner being extinguished the thermocouple cools and cuts off the supply of gas to the pilot burner. The valve mechanism by which this is accomplished is not illustrated as usable thermocouple controlled valves are known to those skilled in the art and as stated, the detail of the valve forms no part of my present invention.

With the parts formed and arranged as illustrated neither the thermocouple jet or the pilot burner jet are likely to be extinguished but should one of them be extinguished the other is promptly relighted. The connections of the jet orifices by means of the slots and the opening of the slots to the outside of the burner insures effective combustion and minimizes the likelihood of either jet being extinguished. The flange 16 as associated with the slots and jet orifices is highly effective in preventing the extinguishing of the jets by drafts of air.

I have illustrated and described my invention in a highly practical embodiment thereof. I have not attempted to illustrate or describe other em-

bodiments or adaptations as it is believed that this disclosure will enable those skilled in the art to embody or adapt my invention as may be desired.

Having thus described my invention, what I claim as new and desire to secure by Letters Patent is:

1. A pilot burner comprising a burner tube adapted to be associated with a gas supply nozzle, and a domed burner head sleeved upon said tube and having an integral annular outwardly extending flange at its inner end, said tube and burner head having registering longitudinal gas outlet slots therein, the slot in the burner head extending to the center thereof, the slot in the burner tube extending substantially below said flange, said burner head having a burner pilot jet orifice in the side thereof disposed at substantially 90° angularly spaced relation to said longitudinal slot in said head, said burner tube having a thermocouple jet orifice opening to said longitudinal slot therein and spaced from said flange and from the inner end of the slot, said burner tube and head having registering diagonal slots therein extending from said burner jet orifice in said burner head and crossing the longitudinal slot in substantially the plane of the flange, said guard having a radial slot therein opening to said slots in said tube and head.

2. A pilot burner comprising a burner tube adapted to be associated with a gas supply nozzle, and a burner head sleeved upon said tube and having an integral annular outwardly extending flange at its inner end, said tube and burner head having registering longitudinal gas outlet slots therein, the slot in the burner tube extending substantially below said guard, said burner head having a burner pilot jet orifice in the side thereof disposed in angularly spaced relation to said longitudinal slot in said head, said burner tube having a thermocouple jet orifice opening to said longitudinal slot therein and spaced from said flange, said burner head having a slot therein extending from said burner jet orifice in said burner head to the longitudinal slot.

3. A gas pilot burner comprising a burner tube, a burner head on said tube, and an annular outwardly extending flange at the inner end of said head, said tube and head having registering longitudinal gas outlet slots extending above and below the flange, said head having a burner pilot jet orifice vertically spaced from said flange and angularly spaced from said longitudinal slot, said burner tube having a thermocouple jet orifice below and spaced from said flange and opening to said longitudinal slot, said head and tube having a diagonal slot crossing the longitudinal slot in substantially the plane of said flange, the flange having a radial slot opening to said longitudinal and diagonal slots.

4. A pilot burner comprising a burner tube adapted to be associated with a gas supply nozzle, and a burner head on said tube, said tube and burner head having registering longitudinal gas outlet slots therein, said burner head having a burner pilot jet orifice disposed in angularly spaced relation to said longitudinal slot in said head, said burner tube having a thermocouple jet orifice opening to said longitudinal slot therein, and an outwardly extending flange disposed between said jet orifices, said burner having a slot therein opening to said burner jet orifice and said longitudinal slot.

5. A gas pilot burner comprising a burner tube, a burner head mounted on said tube, said tube and head having registering longitudinal gas outlet slots, said head having a burner pilot jet orifice vertically spaced from said guard and angularly spaced from said longitudinal slot, said burner tube having a thermocouple jet orifice opening to said longitudinal slot, a slot opening to the longitudinal slot and to said burner jet orifice, and an outwardly extending flange disposed between said jet orifice and in spaced relation to each of them.

6. A gas pilot burner comprising a burner tube provided with a burner head, said tube and head having communicating gas outlet slots, said head having a burner pilot jet orifice connected to said slot therein, said burner tube having a thermocouple jet orifice opening to said slot therein, and an outwardly extending flange disposed between said jet orifices and in spaced relation to each of them.

7. A gas pilot burner comprising a burner tube, a burner head mounted on said tube, said tube and head having connecting longitudinally extending gas outlet slots, and an outwardly extending flange at the juncture of said slots, said head having a burner pilot jet orifice vertically above said flange and angularly spaced from said longitudinally extending slot in said head, said burner tube having a thermocouple jet orifice below said flange and opening to said longitudinally extending slot therein, there being a slot in said head above said flange opening to the said longitudinally extending slot of the head and to said burner jet orifice.
